WALLPAPER BOARD

William M. Clemm, Akron, Ohio

Application March 24, 1939, Serial No. 264,027

6 Claims. (Cl. 33—76)

This invention relates to paper hangers' boards and to improvements in means for mounting a straight-edge thereon.

Objects of the invention are to provide a board having a straight-edge hinged thereto for swinging movement to and from an operative position thereon; to provide strong, durable, quickly adjustable means for hingedly securing a straight-edge in an accurate position on a board; to provide a straight-edge mounting which can be swung beneath the board leaving an unobstructed working space, and which is provided with conveniently adjustable means for accurately setting the straight-edge in two cutting positions whereby the same may be selectively moved to trim either side of the paper.

A further object is to provide means for hingedly mounting a straight edge on a paper hanger's board in which the mounting means is adjustable to boards of different types and thicknesses and which may be used with different types of straight-edges.

A still further object is to provide means for hingedly mounting a straight-edge on a paper hanger's board in which the mounting means is adjustable to boards and straight-edges of different types and thicknesses.

The invention will be hereinafter described with reference to the particular adaptation thereof disclosed in the drawing in which I have shown a preferred form of the invention, it being understood that the invention is not confined to the particular form shown and that changes may be made which come within the spirit of the invention as hereinafter claimed.

In the drawing:

Figure 1 is a plan view of a paper hanger's board constructed in accordance with this invention, parts being broken away to conserve space.

Figure 2 is a cross sectional view taken as indicated by the lines 2—2 of Figure 1.

Figure 3 is a plan view of a piece of wallpaper which is shown to illustrate the following description.

The invention will now be described with reference to the illustrative embodiment thereof shown in the drawing. The numeral 5 denotes a paper hanger's board which may be of any suitable construction which is provided along the forward edge thereof with a flat stop 6. The stop 6 is provided with an inwardly presented straight edge against which one edge of a strip of paper may be positioned to properly position the strip on a board.

The numeral 7 denotes hinge leaves which are secured in spaced relation to the bottom of the board 5 with the knuckle portions 8 turned downwardly. The numeral 11 denotes a co-operating knuckle which is positioned between the knuckles 8 and which is provided with a bore 9 which is in axial alignment with like bores in the knuckles 8 and a pintle 12 is entered in the bores 9 thus hingedly connecting the knuckles 8 and 11. An internally threaded hollow shank 11a projects 5 from the knuckle 11 and a rod 10 having a threaded right angle end portion 10a is operatively positioned therein.

With the shank 11a in a vertical position the rod 10 projects over the board 5 at a right angle 15 to the inwardly presented edge of the stop 6. It will be seen that the portion 10a of the rod 10 can be operated in the hollow shank 11a to position the rod 10 the proper distance above the board 5 and that the adjustable shank can be 20 regulated to fit boards 5 of different thicknesses.

The numeral 13 denotes a straight-edge which may be of any suitable construction and which is provided adjacent each end thereof with a bore 14 in which is received one of the rods 10 25 whereby the straight edge 13 is slidably mounted on the rods 10.

The numeral 15 denotes cylindrical stops, each of which is provided with an axial bore in which is received the rod 10. Each of the stops 15 is 30 provided with a radial, threaded bore in which is operatively mounted a thumb screw 16. Two of the stops are mounted on each rod 10 with a stop 15 positioned on each side of the straight-edge 14, and the stop 15 can be adjustably positioned on the rod 10 and set by operating the screw 16 to limit the movement of the straight-edge 13 thereon.

As shown in Figure 3 the wallpaper 17 is ordinarily provided with a relatively wide margin 40 18 along one side thereof and with an edge portion 19 along the other side thereof. In butting wallpaper, both the margin portion 18 and the edge portion 19 must be trimmed to properly match the paper before the same is applied to 45 a wall.

In use, the rod 10 may be swung downwardly on the hinge 7 to the dotted line position shown in Figure 2. The paper 17 is placed on the board with the edge 19 thereof positioned against the 50 stop 6. The straight-edge 13 is then swung on the rods 10 to the position shown in Figures 1 and 2 and the straight-edge 13 positioned along the edge 19 thereof. The stops 15 are then adjusted to engage the straight-edge 13 and limit 55

the movement thereof toward the forwardly presented edge of the board. The straight-edge is then moved on the rods 10 to place it on the paper 17 to the proper position for cutting the marginal edge 18 and the stop 15 on the free end portion of the rod 10 is set to limit the rearward movement of the straight-edge 13 whereby the straight-edge may be pulled to a forward position to guide the knife or other cutting means which is passed along the forward edge thereof to trim the edge portion 19 and may be quickly and conveniently moved rearwardly to guide a knife or other cutting means in removing the marginal portion 18.

15 The rods 10 with the straight edge 13 may be swung to an inoperative position as shown by the dotted lines in Figure 2 and the board 5 may be used to cut wall paper in desired lengths or to apply adhesive to the paper in the ordinary manner and the rods 10 may be then swung upwardly and the straight-edge 13 used as a trimming guide for either edge 18 or 19.

20 While I have shown a particular form of straight-edge 13, it is understood that any suitable straight-edge may be employed and while I have illustrated a straight-edge intended to be used with a flat knife, it will be understood that a disk knife may be used or sliding cutting devices of various forms may be mounted on the straight-edge and used as herein set forth.

25 While I have shown a rod 10 adjustably connected to the shank 11a, it will be understood that the downturned end portion 10a of the rod 10 may be secured directly to the knuckle 11.

30 Having thus illustrated my invention and described the same in detail, what I claim as new and desire to secure by Letters Patent is:

35 1. In a device of the character described, a board, a strip on the upper face of the board extending along the forward edge thereof with the inwardly directed edge of the strip disposed in a vertical plane, spaced inwardly from said forward edge; arms hinged to said board for swinging movement in vertical planes disposed at a right angle to the forward edge of the board, said arms movable to a horizontal position over the board; a straight-edge slidably mounted on said arms for movement longitudinally thereof and stops on each arm on each side of said straight edge; said stops permitting a limited movement of said straight edge toward and from said strip.

40 2. In a device of the character described, a board, a strip on the upper face thereof extending along the extreme forward portion of said upper face with the inwardly directed edge of the strip spaced inwardly from the forward edge of the board; parallel arms hinged to said board

45 for swinging movement in vertical planes disposed at a right angle to the forward edge of the board, said arms movable from a position below the board to a position over the board; a straight edge slidably mounted on said arms for movement longitudinally of the arms and a stop adjustably secured to each arm on each side of said straight edge, said stops permitting a limited movement of said straight edge toward and from the forward edge of the board.

50 3. In combination with a paper hanger's board having a strip on the upper face thereof extending along the extreme forward portion of said upper face with the inwardly directed edge of the strip spaced inwardly from the forward edge of the board; arms hinged to said board at spaced points for swinging movement in vertical planes disposed at a right angle to the forward edge of the board, said arms movable to a position over the board; a straight edge slidably mounted on said arms for movement longitudinally of the arms and stops adjustably secured to said arms, said stops permitting a limited movement of said straight edge toward and from the forward edge of the board.

55 4. In a device of the character described, a board, a strip on the upper face of the board extending along one edge thereof with the inwardly directed face of the strip spaced inwardly from said edge for engaging the edge of the paper to be trimmed; arms hinged to the board for movement to a position over the board, a straight-edge slidably mounted on said arms, stops adjustably secured to said arms for limiting the movement of said straight-edge on said arms while permitting a limited movement thereof toward and from the inwardly directed face of said strip.

60 5. In a straight-edge mounting for use on a paper hanger's board, arms, hinges for securing said arms to said board for swinging movement in vertical planes disposed at a right angle to the forward edge of the board; said arms movable on said hinges to a horizontal position over the board, a straight edge slidably mounted on said arms for movement longitudinally thereof and stops on each arm, said stops permitting a limited movement of said straight edge longitudinally of said arms.

65 6. In a straight-edge mounting for a paper hanger's board, an arm, a hinge on one end thereof for securing the same to a board for movement to a position over the board, said arm designed to have a straight edge slidably mounted thereon; stops adjustably secured to said arm for restricting the straight edge to a limited movement longitudinally thereon.

WILLIAM M. CLEMM.
